(57) **CLAIM**

The ornamental design for a collapsible trailer for an automotive vehicle, as shown and described.

DESCRIPTION

FIG. 1 is a perspective view of the collapsible trailer for an automotive vehicle of the present invention showing my new design with the dotted lines depicting solely environmental structure and forming no part of the claimed design;

FIG. 2 is a top plan view thereof;

FIG. 3 is a side elevational view thereof;

FIG. 4 is a bottom plan view thereof;

FIG. 5 is a front elevational view thereof;

FIG. 6 is a rear elevational view thereof;

FIG. 7 is a perspective view depicting the collapsible trailer for an automotive vehicle in a stowed configuration;

FIG. 8 is a top plan view thereof;

FIG. 9 is a side elevational view thereof;

FIG. 10 is a bottom plan view thereof;

FIG. 11 is a front elevational view thereof; and,

FIG. 12 is a rear elevational view thereof.
